UNITED STATES PATENT OFFICE.

ARTHUR B. CHADWICK, OF SOUTH WHITLEY, INDIANA, ASSIGNOR TO GRIP NUT COMPANY, OF CHICAGO, ILLINOIS, A CORPORATION OF ILLINOIS.

MACHINE FOR COMPRESSING LOCK-NUTS AND THE LIKE.

1,391,170.

Specification of Letters Patent. Patented Sept. 20, 1921.

Application filed August 24, 1918. Serial No. 251,264.

To all whom it may concern:

Be it known that I, ARTHUR B. CHADWICK, a citizen of the United States, residing at South Whitley, in the county of Whitley and State of Indiana, have invented certain new and useful Improvements in Machines for Compressing Lock-Nuts and the like, of which the following is a description.

My invention belongs to that general class of devices designed to coöperate with other devices in the manufacture of lock nuts to produce the finished product. It is particularly designed to automatically apply pressure to the nuts at some stage of their manufacture, and so controlling said pressure that the treatment shall be uniform to all of the nuts passing through the machine. It is thus designed and is effectively used in the manufacture of that type of lock nuts where the nut is substantially formed, and thereafter sufficient pressure is applied to bring about a slight modification of one or more of the threads in the nut by means of which it is caused to more firmly engage with the coöoperating bolt by reason of the increased frictional engagement of the parts.

It has for its object a novel and effective device of the character described which shall be simple and exact, as well as automatic in its operation.

To this end my invention consists in the novel construction, arrangement and combination of parts herein shown and described and more particularly pointed out in the claims.

In the drawings, wherein like reference characters indicate like or corresponding parts,

Figure 1 is a side elevation of one form of my improved device;

Fig. 2 is a sectional view thereof taken on line 2—2 of Fig. 1;

Fig. 3 is a sectional view taken substantially on line 3—3 of Fig. 2;

Fig. 4 is a transverse view taken on line 4—4 of Fig. 3;

Fig. 5 is a sectional view taken substantially on line 5—5 of Fig. 4;

Fig. 6 is a sectional view taken substantially on line 6—6 of Figs. 1 and 3; and

Fig. 7 is a side view of a treadle and connecting part shown at the bottom of Fig. 1.

In the drawings, 1 represents a suitable base supporting a rotatable vertical shaft 2 in suitable bearings. Upon the upper or

free end of the shaft is carried a plate 3, which therefore rotates in a horizontal plane. The plate 3 has formed therein a series of openings 4 radially arranged therein, of suitable size to receive the nuts 5 to be treated, and rotates upon the horizontal plate or bed 6, which serves as a bottom for the several openings 4 except at the particular point where the nuts are to be discharged into a chute 7, or equivalent part, and at the point where the pressure is applied to the nuts.

One or more inclined chutes 8 convey the nuts from the receptacle 9 downward and discharge them into the openings 4, there being one of such delivery chutes to each row of receptacles or pockets in the series, concentrically arranged about the center of the plate 3. Automatic means are employed to deliver the nuts to the lower end of the chute as desired.

Arranged transversely across the machine is a compressing bar 10, which at its ends is supported upon resilient means 11, and near its center supports at one end a depressible bar 12 extending at right angles thereto, which at its free end is guided by the perpendicular bar 13 provided with a spring 14 (Figs. 2 and 3). The bar 12 extends radially from near the center of the plate 3 outwardly in alignment with a series of the openings 4 during the measured or step by step rotation of the plate 3. A ram or deflecting bar 14^a is carried above the bar 12 by guides or housing 15 (Fig. 1).

The bar 14^a is caused to reciprocate in a vertical direction by connection with an eccentric 16 mounted on the shaft 17. A link 18 extends from the eccentric and is pivotally connected to the ram at 19. This portion of the device is very similar to a well known type of punch press in general use. The reciprocation of the ram brings the lower face thereof downward upon the cross bar 12 at each movement with a tendency to press the bar 12 downward upon the nuts at that moment arranged therebeneath.

Provision must be made for a firm bearing or anvil arranged beneath the nuts which are to be compressed, and as the nuts or the bars from which they are constructed, vary slightly as to thickness, and at the same time the amount of deflection must be equally gaged so as not to deflect the nut too much, this support in my improved device is ar- 110

- ranged to automatically adjust itself to the precise thickness of the nut to secure the exact and same amount of deflection in all the nuts.
- 5 The preferred means employed to accomplish this action is more clearly illustrated in Figs. 2 and 5. As shown, it will be seen that an anvil block 20 is maintained in position beneath each nut to be compressed.
- 10 Each anvil block slidingly rests upon a reciprocating wedge-shaped bar 21, which is guided in its movement in any preferred manner. As shown in Fig. 2, a mortise engagement at the bottom of the block as at 15 22 serves to keep the several bars in proper alignment with the block 20. As shown in Fig. 5, the bars 21 have arranged at either end thereof resilient connections which cause them when moving in one direction to lift 20 the block 20 upward against the nut, bringing the latter in contact with the bar 12. When the compression is completed the bar 12 is released by the upward movement of the ram, the resilient connection at the opposite end forces the bar 21 backward, permitting the block 20 riding thereon to move downward slightly to clear the plate 6, and making ample provision for the reciprocation of the next nut. As clearly shown in 25 30 Figs. 1 and 2, a shaft 22 is driven by sprocket 23 or equivalent means actuated by a chain 24, which at its upper end is carried by a sprocket mounted on the shaft 17. As shown in Fig. 5, this shaft 22 has mounted 30 upon it a cam 25 for each of the wedge bars 21. A movable bar 26 is mounted in guides 27-28, and has secured at one end a roller or anti-friction device 29 coöperating with the cam 25. A spring 30 is mounted in the 35 40 guide 28, at one end bearing against the movable bar 26 and at the other end against the wedge bar 21 which is thus pushed forward in a resilient manner at each rotation of the cam 25. Upon the opposite end of the 45 50 bar 21 is a longitudinally movable bar 31 mounted in a proper guide 32. The opposite end of the bar 31 engages with the wedge bar 21 as at 32^a. A spring 33 is carried loosely on the bar 31 between a shoulder 34 55 60 on the guide 32 and the end of the bar 21. Thus as the bar is forced forward to lift the anvil block upward, the spring 33 is retracted under the positive force of the cam action. However, as the cam rotates to permit the bar 26 to be released from this action, the spring 33 forces the bar 21 backwardly as described, permitting the anvil block 20 to drop slightly from its operative 65 position to clear the plate 6.
- 60 As shown in Fig. 3, the nut chutes 8 are provided with automatic means to periodically release the nuts carried therein so that they may be delivered to the plate singly or one at a time and thus not load it up so as 65 to interfere with its operation. Any pre-ferred means may be employed for this purpose. As shown, an oscillating lever 35 is pivotally mounted upon a stub 36 carried by the slide 8, and is provided at one end with a downwardly projecting extension 37, and at the opposite end with a downwardly extending pin 38. These two parts are positioned a sufficient distance apart so that in its normal position and with the ram at its upper location, the extension 37 extends down in front of the forward nut 5, holding all the nuts in the rear thereof immovable. As the oscillating lever 35 is forced downward, the pin 38 enters into the bolt hole of the nut 5 beneath the same, holding all of the nuts back of that one in place, and the end of the lever moves downward gradually lifting the extension 37 until the first nut is released and moves downward and is delivered from the end of the chute. The reverse movement brings the parts back to their normal position as shown in Fig. 3. A link 39 connects the end of the lever 35 to the end of a reciprocating plunger 40, which is mounted on an extending arm 41 rigidly secured to the reciprocating ram 14^a. In the preferred construction a nut 42 is mounted upon the upper end of the rod 40, and a spring 43 is positioned on the rod between the nut and the arm 41. A similar nut 44 95 may be secured upon the rod 40 below the arm 41 and a spring 45 mounted thereon. This secures a resilient action of the lever 35 so that in case the pin 38 does not properly engage the nut 5, or any other obstruction 100 occurs, the parts will not be broken.
- Referring to Figs. 3 and 6, a shaft 46 is driven by a sprocket 47 and a chain 48 extending upward and mounted upon a sprocket carried upon the shaft 22 or by 105 equivalent means. A cam 49 is mounted upon the shaft 46, and in its rotation reciprocates a bar 50 having upon its end an anti-friction roller 51 contacting with the cam. Referring to Fig. 6, it will be seen that the bar 50 carries an extending arm 52 provided with a spring pawl 53 coöperating with a ratchet 54 fixed to the end of the shaft 2. The opposite end of the bar 50 is supported in any suitable manner by a 110 bearing 55 which it slidably engages, and a spring 56 is mounted between said bearing 55 and a collar 57 carried on the bar 50. It will thus be seen that at each rotation of the shaft 46 the bar 50 is reciprocated, rotating the shaft 2 by means of the ratchet in a step by step motion, the spring 56 returning the shaft 50 to its normal position as the cam releases it. 115
- From this description it will be seen that 120 the action is as follows: Assuming that the machine is ready for use with the nuts in the several guide chutes 8 as indicated in Fig. 3, the plate 3 on the shaft 2 will be rotated in a step by step movement, while 125 130

the ram 14^a will be regularly reciprocated by reason of the continuous rotation of the shaft 17 and the cam carried thereon. The initial downward movement releases the 5 lowermost nut 5 in the chutes 8 which by gravity moves downward and is deposited in one of the openings 4 which at that moment is beneath the same, the parts being so timed for that purpose. As the plate 3 10 continues to rotate in a step by step movement as described, nuts will be successively deposited in the radially arranged openings 4 therein. When the nuts first positioned in the plate reach a point over the 15 anvil block 20, at which point the plate is cut away, the nuts drop through the plate and for the moment rest upon the blocks 20 and beneath the bar 12. At this moment the wedge blocks 21 are moved forward, 20 lifting the anvil blocks upward and resiliently pressing the nuts against the bar 12, while at the same time forming a solid foundation for the pressure of the ram. The descending ram contacts with the upper 25 face of the bar 12 and presses the same downward a distance gaged by the eccentric driving the same.

The several wedge bars 21 being independently driven forward and resiliently 30 cushioned as stated, each brings the nut above it upward in positive contact with the compression bar 12, independently of the operation of the other wedge bars, so that the compression and deflection in the 35 several nuts is exactly the same and brought about simultaneously by the action of the ram.

Referring to Fig. 5, it will be seen that the upper surface of the anvil block at this 40 moment is slightly above the upper surface of the plate 6. It is lifted to this position after the plate 6 has come to a rest and the nut has dropped through the opening in the plate 6 upon the upper surface of the anvil block 20, which normally is 45 slightly below the lower face of the plate 6. After the nuts have been compressed, the wedge bars begin to move backward, and at the moment the upper face of the anvil 50 block comes slightly below the lower face of the plate 6, the plate moves forward in its next action and the nuts are swept upon the upper surface of the plate and thus carried about until they are finally dropped through the 55 plate at the point marked 58 into the slide 7, where they are conveyed to such points as may be desired.

As before mentioned, the reciprocating portion of this machine and its connecting 60 parts are similar to a well known type of punch press now in general use. In such punch presses, the outline of which is shown in the drawings, the operation of the machine is usually controlled by a foot lever.

65 By means of the foot lever the machine may

be caused to operate continuously, maintaining in the present device the step by step operation of the rotating plate, or the machine may be stopped for any desired purpose. In Fig. 1 such a foot lever is shown 70 as at *n*. The usual connection is made between the foot lever with any preferred form of clutch mechanism (not shown) by means of which the operation of the machine may be controlled. 75

As shown in Figs. 1 and 7, a retaining device *o* is arranged with a hook *p* and is pivotally supported at *r* so that if desired when the foot lever is depressed the hook may engage the shank of the foot lever, as 80 shown in Fig. 7, and maintain the same in that position until it is desired to release it. This may be readily done by pressing downward on the extension *s* connected with the engaging means which will withdraw the hook from over the shank of the foot lever and release the same. 85

Having thus described my invention, it is obvious that various immaterial modifications may be made in the same without departing from the spirit of my invention as defined in the appended claims; hence I do not wish to be understood as limiting myself to the exact form construction, arrangement and combination of parts herein shown 90 and described, or uses mentioned.

Having thus described my invention, what I claim as new and desire to secure by Letters Patent is:—

1. In a machine of the kind described, a compressing element, a coöperating reciprocating part arranged to depress said element, and mechanism for reciprocating said part, in combination with a movable anvil block arranged beneath the compressing element, and means for moving said anvil to operative position to support a nut between said element and the block during the compression operation. 100

2. In a machine of the kind described, a compressing element, a coöperating reciprocating part arranged to depress said element, and mechanism for periodically reciprocating said part, in combination with a movable anvil block arranged beneath the compressing element, and means timed with the reciprocation of said reciprocating part for moving the anvil block to operative position to support a nut between said element and the block during the compressing operation. 110

3. In a machine of the kind described, a compressing element, a coöperating reciprocating part arranged to depress said element, and mechanism for periodically reciprocating said part, in combination with a movable anvil block arranged beneath the compressing element, means timed to the reciprocation of said part for elevating the anvil block to support a nut between said element and the block during the compressing opera- 125

- tion of the reciprocating part, and means for delivering a nut upon said anvil block in position to be acted upon, substantially as described.
5. 4. In a machine of the kind described, a compressing element, a reciprocating part arranged to depress said element, and mechanism for periodically reciprocating said part, in combination with a movable anvil block arranged beneath the compressing element, and resilient means timed to the reciprocation of said reciprocating part for moving the anvil block toward the compressing element to support a nut between said element and the block during the compressing operation.
5. In a machine of the kind described, a compressing element, a coöperating reciprocating part arranged to depress said element, 20 and mechanism for reciprocating said part, in combination with a movable anvil block arranged beneath the compressing element, and automatic means timed to the reciprocation of said part for moving the anvil block 25 to a position to support a nut between said compressing element and the block during the compressing operation.
6. In a device of the kind described, a compressing element, a coöperating reciprocating part arranged to depress said element, and mechanism for reciprocating said part, a movable anvil block arranged beneath the compressing element, and automatic means for moving the anvil block to support a nut 35 between said element and the block during the compressing operation, in combination with a rotating plate having formed therein one or more cells adapted to receive a nut, means for rotating said plate to bring the 40 nut coincidentally beneath the compressing element in time to be operated upon thereby, and means for discharging the nut operated upon during the reverse movement of the reciprocating part and bringing another 45 nut in position to be operated upon as the reciprocating part again descends to operative position.
7. In a machine of the kind described, a compressing part, means for periodically operating said part, and an anvil block beneath the compressing part, in combination with a rotating plate operated by a step by step motion, one or more cells formed in said plate to receive nuts, a stationary plate arranged beneath said rotating plate to form 55 a floor for said cells cut away at a point above said anvil block to permit the nuts to drop thereon, and means for discharging the nuts operated upon, substantially as described.
60. 8. In a device of the kind described, a vertically movable anvil block and means for maintaining the same in relative operative position, in combination with a longitudinally movable elevating block upon 65 which the anvil block is slidably mounted, means for resiliently forcing said elevating block beneath said anvil block to bring the latter into operative position, and means for thereafter moving said elevating block backward to bring the parts to their normal positions.
9. In a machine of the kind described, a vertically movable anvil block, means for maintaining the same in operative position, 70 a longitudinally movable elevating block upon which the anvil block is slidably mounted, means for longitudinally moving the elevating block forward and backward to alternately elevate the anvil block to operative position and then let it recede, a co-operative compression member arranged above the anvil block, and means for periodically applying operative pressure thereto to compress a nut between the said member and the block, in combination with a plate rotating between the same member and anvil block having formed therein open cells for the reception of bolt nuts, a fixed plate forming a bottom for the cells but open 75 about the anvil block, and mechanism for rotating the cell plate step by step to present the nuts therein between the compression member and the anvil block.
10. In a machine of the kind described, a series of vertically movable anvil blocks, means for maintaining the same in operative position, means for elevating the blocks periodically, a coöperating compression bar arranged above the blocks and means for periodically applying operative pressure to said bar to compress bolt nuts positioned between the bar and the anvil blocks, in combination with a fixed horizontal plate extending with its upper face substantially in line with the top face of the anvil blocks 100 when the latter are in inoperative position and having openings formed therein within which the upper part of the anvil blocks protrude, a rotating plate above the fixed plate having a plurality of series of nut cells formed therein so arranged that as the plate is rotated the series of nut cells will be successively brought into alinement with the anvil blocks, and mechanism for rotating the said plate step by step, substantially as described.
105. In testimony whereof I have hereunto signed my name in the presence of two subscribing witnesses.
110. ARTHUR B. CHADWICK.
